Filed June 1, 1961, Ser. No. 114,136
5 Claims. (Cl. 92—33)

This invention relates to improvements in hydraulic mechanisms and more particularly to improvements in hydraulic torque actuators.

It is conventional practice to utilize hydraulic pressure in the actuation of devices requiring a large amount of torque such as, for instance, aircraft flaps or the like. The conventional method of utilizing hydraulic power in this respect is by means of a hydraulic jack incorporating a piston and jack ram, the jack ram being caused to move inwardly or outwardly of the jack depending on the side of the piston to which the hydraulic pressure is applied, and this reciprocal action of the jack ram is transmitted through an arcuately operating lever to cause the flap or the like to move through an arc of, usually, 90°.

The disadvantages of this conventional system are that the jack must pivot during the operation and therefore, may be pivotally attached to the surrounding structure at one end only. The jack ram also may become contaminated with sand or the like while in the extended position and, upon being retracted, this sand destroys the seal and permits hydraulic fluid to leak from the jack. An additional disadvantage lies in the fact that the lever attached to the flap or the like requires a large amount of space in which to operate and the connection between the end of the jack ram and the lever must be in the form of a pivot pin which is liable to excessive wear and, due to human error, may not be properly secured and may thus endanger the aircraft and crew. Also, upon being used to operate aircraft flying controls or the like, the complete mechanism is extremely difficult to streamline. Furthermore, due to the arcuate movement of the jack body, the pipelines conducting the hydraulic fluid to and from the jack must necessarily be flexible causing them to be far more difficult to manufacture and more prone to leakage than rigid pipelines.

It is an object of this invention to provide a hydraulic torque actuator that will convert the reciprocating motion of a piston into rotary motion of a shaft within the unit itself.

It is another object of this invention to provide a hydraulic torque actuator which may be rigidly affixed to the structure adjoining the mechanism to be rotated.

It is still another object of this invention to provide a hydraulic torque actuator which will eliminate pivot pins and the like by being keyed directly to the hub of the mechanism to be actuated.

It is a further object of this invention to provide a hydraulic torque actuator which may be supplied with hydraulic fluid through rigid pipelines, thereby cutting down the cost of installation and lowering the possibility of pipeline leakage.

It is yet another object of this invention to provide a hydraulic torque actuator which may be completely streamlined in the smallest possible space due to the fact that the actuator body does not move during operation.

It is still another object of this invention to provide a hydraulic torque actuator which may have the operating shaft thereof caused to rotate through any desired number of degrees during a single stroke of the operating piston.

It is yet another object of this invention to provide a hydraulic torque actuator in which internal wear and leakage is minimized by means of utilizing a static piston

2

seal in direct contrast to a hydraulic jack in which the seal must necessarily move with the piston.

These and other objects and features of this invention will become apparent when taken in conjunction with the accompanying drawings in which:

FIG. 1 is a mid vertical sectional side elevation of a hydraulic torque actuator embodying this invention.

FIG. 2 is a transverse section of the hydraulic actuator as illustrated in FIG. 1 taken on the line 2—2 and illustrating particularly the method by which rotation of the operating piston is prevented.

FIG. 3 is a transverse section of the hydraulic actuator as illustrated in FIG. 1, taken on the line 3—3 and illustrating particularly the method by which the centre shaft is caused to rotate upon operation of the piston.

Referring to FIG. 1, a torque actuator 10 comprises a cylinder assembly 11, a piston assembly 12 and a torque shaft 13. Cylinder assembly 11 comprises two open ended cylinders 14 and 15 in axial alignment, the open end 16 of cylinder 14 bearing a flange 17 adapted to extend both internally and externally of cylinder 14. Cylinder 15 carries a similar flange 18 at its open end 19. Flange 17 of cylinder 14 and flange 18 of cylinder 15 are adapted to be joined substantially in face to face relationship by conventional means, such as for instance, bolts.

An outwardly facing annular recess 20 is formed at the inner edge of flange 17 and a similar recess 21 is formed in flange 18, recesses 20 and 21 being adapted to house two oppositely facing V-type sealing rings 22 and 23 respectively, V-ring 22 being adapted to prevent fluid escape from the bore of cylinder 14 and V-ring 23 being adapted to prevent fluid escape from the bore of cylinder 15. An annular plate 24 is interposed between rings 22 and 23 and sealably recessed into the outer surfaces of flanges 17 and 18 of cylinders 14 and 15 respectively, plate 24 being adapted to provide a rigid structure for the outermost surfaces of rings 22 and 23 and to support them under pressure.

An end wall 25 of cylinder 14 is bored centrally to accommodate a bush 26 which extends through and outwardly of end wall 25 to be supported in a block 27 formed centrally on the outer surface of end wall 25, bush 26 being adapted to rotatably support one end 28 of torque shaft 13. An end cover plate 29 is sealably fitted over the outer surface of block 27 by conventional means, such as for instance, screws.

The opposite end 30 of shaft 13 similarly passes through an end wall 31 of cylinder 15 and is similarly supported by a bush 32 located within a block 33, and due to end 30 of shaft 13 extending outwardly beyond block 33, a V-ring type seal 35 is housed in a conventional manner within block 33 and retained therein by end plate 34.

It should be noted that ends 28 and 30 of shaft 13 are of reduced diameter thereby forming two oppositely located shoulders 36 and 37 respectively on shaft 13. A ball thrust bearing 38 is fitted over end 28 of shaft 13 and is adapted to absorb axial pressure exerted on shaft 13 between shoulder 36 of shaft 13 and the inner surface 60 of end wall 25 of cylinder 14. Similarly, a thrust bearing 39 is located between shoulder 37 and the inner surface of end wall 31 of cylinder 15 to absorb axial pressure in the opposite direction.

A conventional hydraulic fitting 40 passes through end wall 25 of cylinder 14 to permit hydraulic fluid under pressure to be supplied to cylinder 14, a similar hydraulic fitting 41 is located through end wall 31 of cylinder 15 to supply hydraulic fluid to the interior of cylinder 15.

Referring to FIGS. 1 and 3, piston assembly 12 comprises an inner cylinder 45 and an outer cylinder 46, cylinders 45 and 46 being coaxial with shaft 13. Inner cylinder 45 is slidably mounted on shaft 13 by means of

a bushed end block 47 forming a rear wall thereof and located adjacent end 28 of shaft 13. The opposite end of inner cylinder 45 is supported by a bushed block 48 which is attached to a flanged portion 49 located at the end of cylinder 45 by means of a plurality of bolts 50.

Two oppositely located, mutually inclined helical slots 51 and 52 are formed throughout the length of inner cylinder 45, slots 51 and 52 being adapted to accommodate two rotary bushes 53 and 54 respectively. Two spool members 55 and 56 are adapted to rotatably retain bushes 53 and 54 respectively, spools 55 and 56 extending radially outwardly, diametrically oppositely, from a collar 57 which forms an integral part of shaft 13 and is located substantially centrally thereon. A bolt 44 passes through spool 56 and diametrically through collar 57 to threadably engage spool 55 thereby retaining spools 55 and 56 with their respective bushes 53 and 54 substantially integrally with shaft 13.

Referring to FIGS. 1 and 2, it may be noted that two bolts 58 and 59 are diametrically oppositely located in, and extend radially outwardly from, block 48 within the bore of cylinder 15, bolts 58 and 59 being adapted to rotatably support two double bushing assemblies 60 and 61 respectively.

Double bushing assemblies 60 and 61 are adapted to cooperate within two straight longitudinal slots 62 and 63 respectively formed within the inner surface of cylinder 15 and extending for the full length thereof.

The function of the foregoing mechanism is to permit inner cylinder 45 of piston assembly 12 to reciprocate within cylinder assembly 11 and to eliminate any tendency to rotate therein.

It may be seen, therefore, that reciprocation of cylinder 45 causes slots 51 and 52 formed therein to move past bushes 53 and 54 on spools 55 and 56. In this manner, bushes 53 and 54 are forced to follow the contour of slots 51 and 52, and through bolt 44 and collar 57, cause shaft 13 to rotate.

Outer cylinder 46 is provided to furnish a fluid proof barrier between the bores of cylinders 14 and 15, to achieve this end, the walls 64 of cylinder 46 are in permanent, sliding, contact with V-rings 22 and 23 as previously described and its end wall 65 is screwably attached to end block 47 of inner cylinder 45, a double acting, V-ring type seal assembly 66 being suitably located within end block 47 and end wall 65 of cylinders 45 and 46 respectively, thus permitting piston assembly 12 to move slidably along shaft 13 while preserving the fluid tight integrity between the interior of piston assembly 12 and the interior of cylinder 14.

An O-ring 68 is also located between end block 47 and end wall 65 to prevent leakage therebetween.

Referring to FIG. 2, two substantially semi-cylindrical portions 69 and 70 are located longitudinally within cylinder 15, their adjacent longitudinal edges being in parallel spaced apart relationship thereby forming slots 62 and 63.

Referring to FIG. 1, the full operation of actuator 10 is as follows: From the position as illustrated, fluid under pressure may be permitted to enter cylinder 14 through hydraulic fitting 49 and, by means of suitable valving, fluid contained within cylinder 15 is permitted to return to the reservoir of the hydraulic circuit, and therefore, fluid pressure acting on end wall 65 of piston assembly 12 causes piston assembly 12 to move longitudinally into cylinder 15. Shaft 13 is thereby caused to rotate as previously described. Pressure leakage from cylinder 14 into cylinder 15 is prevented by V-ring 22 on walls 64 of outer cylinder 46. Similarly, pressure leakage around shaft 13 is prevented by double seal assembly 66.

An opposite selection of the hydraulic valve assembly causes a relief of pressure from the interior of cylinder 14 and an application of pressure within cylinder 15. This pressure acts mainly on the outer surfaces of block 48 which is substantially equal in effective area to end

5 wall 65 of piston assembly 12 and therefore, piston assembly 12 is caused to move out of cylinder 15 and into cylinder 14 and shaft 13 thereby caused to rotate and return to its original position. Pressure leakage from cylinder 15 into cylinder 14 is prevented by the action of V-ring 23 on walls 64 of outer cylinder 46. Furthermore, any tendency for fluid to leak from within piston assembly 12 into cylinder 14 along shaft 13 is prevented by double seal assembly 66. O-ring 68 also effectively prevents leakage between the mating surfaces of end block 47 of inner cylinder 45 and end wall 65 of outer cylinder 46.

It should be noted that in the translation of reciprocal movement of piston assembly 12 into rotation of shaft 13, the forces acting on shaft 13, through bolt 44 and its associated bush and spool assemblies, may be resolved into lateral and longitudinal components. The lateral force determines the amount of torque developed by shaft 13, the longitudinal force merely applying a non-useful, axial thrust to shaft 13. Thrust bearings 38 and 39, in conjunction with shoulders 36 and 37 respectively, are adapted to prevent axial travel of shaft 13 and minimize friction between shaft 13 and end walls 25 and 31 of cylinders 14 and 15 respectively.

Actuator 10 may be anchored to any rigid structure by conventional means and end 39 of shaft 13 may have a keyway 71 formed therein or some other conventional drive method may be incorporated therewith, so that, upon being attached to the centre of a flap or the like, the flap may be caused to rotate.

It may be seen that the effective range of rotation of shaft 13 is determined by the number of convolutions formed by slots 51 and 52 in inner cylinder 45 of piston assembly 12.

Should the desired degree of rotation of shaft 13 be such that slots 51 and 52 are required to be too steeply sloped, slots 62 and 63 in cylinder 15 may also be angularly disposed in a similar manner to slots 51 and 52. This causes the whole of piston assembly 12 to rotate during its linear travel, thereby imparting added movement to shaft 13. Slots 51 and 52 may, therefore, remain at a lesser angle and still the desired extra degree of rotation of shaft 13 may be achieved.

The general design of the individual parts of the invention as explained above may be varied according to requirements in regards to manufacture and production thereof, while still remaining within the spirit and principle of the invention, without prejudicing the novelty thereof.

50 The embodiments of the invention in which an exclusive property or privilege is claimed are defined as follows:

1. A hydraulic torque actuator including a cylinder assembly, a piston assembly and a torque shaft; said cylinder assembly comprising a first cylinder having a closed end wall and an open end and a second cylinder having a closed end wall and an open end, each of said open ends being flanged and said flanges joined to unite said cylinders at their open ends in axial alignment; peripheral sealing means between said flanges extensible into the bore of said cylinder assembly; said piston assembly comprising integral, coaxial inner and outer hollow cylindrical members; first and second end wall maintaining said cylindrical members substantially fluid-tight; said piston assembly being axially slidable within said cylinder assembly, the end embodying said first end wall remaining within said first cylinder, the end opposite embodying said second end wall remaining within said second cylinder and the outer surface of said outer cylindrical member being in slidably, fluid tight contact with said peripheral sealing means; said first cylinder having a longitudinally slotted inner wall; radial extensions from said first end wall of said outer cylindrical member of said piston assembly slidably cooperable with said slotted inner wall to maintain said piston assembly in a predetermined path upon moving within said cylinder assembly; said torque shaft extending

axially through said cylinder assembly and being sealably and rotatably supported by said closed ends thereof; said torque shaft passing axially through said piston assembly in rotatable, sealed relationship; said inner cylindrical member of said piston assembly being helically slotted substantially throughout the length thereof; spool means extending radially outwardly from said torque shaft slidably cooperable with said helically slotted inner cylindrical member; said torque shaft being in shouldered cooperation with said closed ends of said cylinders to restrain said shaft from axial movement while permitting free rotary movement thereof; and adapter means in each of said closed ends of said cylinder assembly to permit the selective ingress and egress of fluid to said first and second cylinders.

2. A hydraulic torque actuator as defined in claim 1, said first cylinder having a plurality of straight, longitudinal slots formed in said inner wall thereof; and said radial extensions having double bushings thereon, closely but freely cooperable within said slots to permit free axial but non-rotatable movement of said piston assembly within said cylinder assembly.

3. A hydraulic torque actuator as defined in claim 1, said first cylinder having a plurality of mutually inclined

longitudinal slots formed in said inner wall thereof; and said radial extensions having double bushings thereon, closely but freely cooperable within said slots to permit free axial and controlled rotatable movement of said piston assembly within said cylinder assembly.

4. A hydraulic torque actuator as defined in claim 1, said inner cylindrical member of said piston assembly having a plurality of mutually inclined helical slots formed therein and said spool means having bushings thereon closely but freely cooperable within said helical slots, axial movement of said piston assembly causing said shaft to rotate.

5. A hydraulic torque actuator as defined in claim 1 in which at least one end of said torque shaft extends beyond said closed end walls and drive means integral with said shaft end.
